FOLDING BRACE FOR IRONING TABLES AND
THE LIKE

Henry J. Gilbert, deceased, late of Saginaw, Mich., by Charles T. Gilbert and Harwood J. Gilbert, Saginaw, Mich., executors; said Gilbert assignor to Saginaw Manufacturing Co., Saginaw, Mich., a corporation of Michigan

Refiled for abandoned application Serial No. 330,849, January 7, 1929. This application July 29, 1932, Serial No. 626,110

6 Claims. (Cl. 68—10)

This invention is a folding brace for collapsible tables such as ironing tables in which the brace when extended is subjected to considerable endwise thrust and hence must be capable of withstanding strains of compression in the lengthwise direction and also transverse strains tending to bend or spring the brace in a flatwise direction.

An object of the invention is to provide a brace consisting of two members hinged together and shaped to engage each other in complementary telescoping relation when folded, the end portion of one of the braces resting inside the other and enveloped and reinforced or stiffened by it.

A further object is to provide a brace constituted as above described wherein the enveloping or trough-like member of the brace is shaped at its other end to provide a pair of spaced bearings that constitute a wide base that acts as a spacer or distance piece between the two side members 20 of the diagonal leg of an ironing table. The said two bearings and their pivot pin also serve to hold the enveloping member of the brace rigidly, enabling it to better resist the sidewise springing tendencies that are brought upon it while the 25 table is in use.

Another object is to provide a light, yet strong brace of the kind described capable of being assembled from a single flat bar member and two other members each made of a single piece of 30 sheet metal, one of these two members being a gravitational slide, the other constituting the above-mentioned trough-like member.

A further object is to provide a gravitational locking sleeve adapted to slide into locking engagement with the end of the complementary enveloping member when the brace is in extended position, the locking action being attained by two locking tongues, one at each side of the brace.

With the foregoing and certain other objects 40 in view, which will appear later in the specification the invention comprises the devices described and claimed and the equivalents thereof.

In the drawing Fig. 1 is a side view of an ironing table embodying the improvement.

Fig. 2 is an enlarged side view showing the jointed brace in partly folded positions, one position shown in dotted lines.

Fig. 3 is a view partly broken away, showing the brace in locked position, as seen from the direction of the arrow in Fig. 1.

Fig. 4 is a detail in perspective showing the sleeve in locked position.

Fig. 5 is a detail in perspective showing the double-tongued sleeve retracted.

As is clearly shown in the drawing the im-

proved brace consists of a flat bar 1 hinged at its upper end to the cable 2, and a co-operating brace member, preferably trough-shaped, 3 whose lower end is hinged by pivot pin 4 to the lower part of the diagonal leg 5 of the table in the 60 manner shown in Fig. 3. An end of bar 1 is received between two longitudinal side flanges 6, 7 on the trough-like sheet metal brace member 3 and is pivoted thereto by rivet pin 8 located a short distance from its end. The other end of 65 the trough-shaped sheet metal brace member 3 has its flanges spaced farther apart. These flanges are received between the two members of the bifurcated table leg and fit closely therebetween.

Thus is provided a wide base 9 on the pivoted trough-shaped member 3, imparting to it and to bar 1 great endwise rigidity when the table is in use. Member 3 is of such shape that it can be made preferably of relatively light sheet metal 70 and easily formed in a die or press.

When the brace members 1, 3 are in folded position, the extremity of the bar member 1 and a portion of its length are concealed within and protected by member 3 and when the brace is 80 extended its two flanges 6, 7 lie closely alongside bar 1 and provide side supports that effectually prevent any undue lateral movement or sidewise play in the pivoted joint 8.

To lock the two brace members 1 and 3 when extended, there is preferably provided a notch 10 on each of the two side flanges 6 and 7 of part 3, and upon the flat bar 1 there is slidably mounted a sleeve 11 formed of sheet metal, one end presenting two tongues 12, arranged to be received in the respective notches 10. Thus are provided two sets of interlocking tongues and notches, one at each side. When they are in engagement the walls 11a of the sleeve that overlie the edges of the bar 1 prevent the brace from 95 folding. Obviously the notches may be in the sleeve 11 and the tongues 12 on member 3 if desired, without departing from my invention as defined in certain of the claims.

By the means above described there is produced a strong rigid brace that is especially well adapted for use in ironing boards and the like, that can be cheaply manufactured of relatively light material and is easily assembled.

Preferably the brace construction is made as 105 above described to permit the use of two interengaging notches and tongues, one at each side of the bar for imparting double locking strength to the sleeve, thereby reducing the liability of accident by reason of possible breakage of one 110

of the tongues, although a single locking device may be provided if desired.

Having thus described the invention, what is claimed and desired to be secured by Letters 5 Patent is:

1. An ironing table having in combination a folding brace including a bar and a co-operating base member, an end of said bar received between flanges of said base member near an end 10 thereof and pivoted thereto, and means for interlocking said bar and base member in extended position, the flanges at the end portions of the base member remote from the pivot being spread apart to present a width greater than the width 15 between the flanges at the joint, said base member being adapted to be received between the branch members of a bifurcated leg of said table, and a pivoted connection therefor whereby there is provided for said folding brace a wide-spreading 20 base member that holds the brace rigidly against tendency to spring sidewise when the table is in use.
2. In a folding brace including a bar and a co-operating trough-like flanged member formed of sheet metal, an end of said bar closely received 25 between flanges of said trough-like member near an end thereof and pivoted thereto, and means for interlocking said bar and member in extended position, an end of the trough-like member having flanges spread apart to provide a 30 base of greater width than the remainder of the trough, said base adapted to be received between the members of a bifurcated table leg, and a pivoted connection therefor, for the purposes set forth.
3. In a folding brace including a bar and a co-operating flanged trough-like member, said bar having an end received between flanges of said trough-like member near an extremity thereof 35 and pivoted thereto, a sleeve slidable on said bar, a side wall of said sleeve formed to releasably engage said trough-like member in locking relation, the ends of the flanges near the other end of said trough-like member spaced apart 40 so as to present a base of greater width than the above mentioned pivoted extremity of the trough, for the purposes set forth.
4. In an ironing table including a board and

a diagonally disposed bifurcated leg hinged at its upper ends to the board and consisting of two downwardly convergent members, a brace member made of sheet metal and having longitudinal flanges whose lower ends are spread apart sufficiently to present a base portion that fits closely between said members near their lower ends and a pivot pin extending through the flanges of said leg members near their lower ends, said flanges being convergent upwardly and formed with notches in their upper ends, a flat bar hinged at its upper part to the board, its lower part received between said flanges and pivoted thereto, and a sleeve slidable on said bar and formed with projecting tongues adapted to be received in said notches. 80 85 90

5. An ironing table having, in combination with downwardly convergent leg members, a foldable brace consisting of a bar hinged at its upper end to the table, a spacer member adapted to telescope with said bar and having longitudinal members separated to present a wide base and pivotally connected respectively to the opposite inner faces of said leg members near the lower ends thereof, parts of said longitudinal 100 members remote from said pivotal connections being convergent, an end of said bar being closely received between the convergent ends of said flanges and pivotally connected thereto, and releasable locking means associated with the hinge 105 of the bar. 95

6. An ironing table having in combination with hinged legs, a foldable brace consisting of a bar hinged at its upper end to the table, a spacer hinged at its upper end to the lower end of 110 said bar and having longitudinal members spaced apart at their lower ends to form a wide base, each of said longitudinal members being arranged for pivotal connection with a bifurcation of a leg member of said table and being adapted to 115 fit between the bifurcations, the upper end of said spacer being arranged to enclose the adjacent end of said bar. 120
